UNITED STATES PATENT OFFICE.

WALTER T. CHARLES, OF CHICAGO, ILLINOIS.

FIRE-EXTINGUISHER.

1,170,513.

Specification of Letters Patent.

Patented Feb. 8, 1916.

Application filed February 24, 1914. Serial No. 820,612.

To all whom it may concern:

Be it known that I, WALTER T. CHARLES, a citizen of the United States of America, and a resident of Chicago, county of Cook, 5 and State of Illinois, have invented certain new and useful Improvements in Fire-Extinguishers, of which the following is a specification.

The main objects of this invention are to 10 provide an improved form of syringe particularly adapted for use in discharging fire extinguishing fluids; to provide an improved arrangement of the pumping mechanism in the fluid container; to provide improved 15 means for insuring the suction of the fluid from the lowest end of the container regardless of the angle at which it is held when operated; to provide improved means for closing the nozzle when the device is not in 20 use; and to provide improved means for controlling the admission of air to the container to replace the fluid as it is forced therefrom.

An illustrative embodiment of this invention is shown in the accompanying drawings, in which—

Figure 1 is a sectional elevation of a fire extinguisher or syringe embodying the foregoing improvements. Fig. 2 is an enlarged 30 fragmentary sectional detail of one end of the suction tube which is connected to the pumping mechanism.

In the construction shown in the drawings the device comprises a cylindrical casting or container 3 the ends of which are closed by caps 4 and 5. A nozzle 6 is secured in the cap 5 and has an aperture 7 through which the fluid is discharged. A fitting 8 is secured within the cap 4 by means 40 of the nut 9 and coacts with a fitting 10 for supporting the pumping mechanism within the container.

The pumping mechanism includes a cylinder 11 concentrically arranged within the container 3, and supported at its ends in the fittings 8 and 10. The cylinder is provided with an inlet 12 at its lower end, and an outlet 13 at its upper end. A piston 14 is 45 slidably mounted in the cylinder 11 and connected to a piston rod 15 which is herein shown in the form of a tube, and which in the operation of the pump serves as a plunger acting to displace liquid from the

cylinder during the downward stroke of the piston.

The fitting 10 is provided with a passage 16 which communicates with the cylinder inlet 12, and a passage 17 which communicates with the nozzle passage 7 by means of the tube 18 concentrically arranged within 55 the container 3 so as to support the fitting 10. An elbow 19 connects the passage 16 with a suction pipe 20 extending along the cylinder 11 and terminating at the ends of the container 3. A tube 21 supported at its 60 ends in the fittings 8 and 10 extends along the opposite side of the cylinder 11 and connects the cylinder outlet 13 with the passage 17 in the latter fitting.

Valve mechanism is provided for controlling the flow of fluid from the container into the cylinder 11 and out through the 70 passages leading to the nozzle 6. This mechanism is preferably in the form of ball valves 22 and 23 respectively located in the 75 passage 16 of the fitting 10 and in the cage 24 formed in the piston 14. The ball valves 22 and 23 are normally urged onto their seats by gravity or their buoyancy in the fluid. The valve 22 permits the fluid to 80 flow into the cylinder 11 when the piston is drawn upwardly, but prevents its return when the piston is pushed downwardly. The valve 23 permits the fluid to pass the piston into the upper part of the cylinder 11 85 when the piston is forced downwardly, and prevents its return as the piston is drawn upwardly. A pin 25 prevents the ball 22 from being withdrawn into the cylinder 11 in case the inlet 12 should be larger than the 90 ball, as might be the case in larger constructions than that herein shown.

A valve 26 is located in the passage 17 in position to shut off communication through the tube 18. The stem 27 of the valve is 95 slidably mounted in the fitting 10 and extends into the cylinder 11 of the pumping mechanism in position to be engaged by the piston so that when the pumping mechanism is contracted with the piston in its 100 lowermost position the valve 26 is shifted to close the passage through the tube 18. A head 28 is carried by the stem 27 which closes the passage through the piston 14 when the piston is forced into engagement 105 therewith. A spring 29 normally urges the

valve 26 to open communication to the discharge nozzle 6 when the piston is drawn upwardly in the cylinder 11.

The suction pipe 20 has the ends thereof open so as to provide ports 30 through which the fluid may be drawn into the cylinder 11. Sleeves 31 are slidably mounted on the ends of the pipe 20, and have attached thereto the caps 32 adapted to form closures for the ends of the pipe 20. Ports 33 are formed in the sides of each of the sleeves 31 by means of which communication is provided with the pipe 20 at one end when the corresponding sleeve is shifted so as to retract the cap 32. Washers 34, preferably of leather, are carried by the caps 32 and are designed to form substantially air-tight closures for the ends of the pipe 20. The sleeves 31 are connected together by an intermediate part 35 which is herein shown in the form of an integral tube embracing the pipe 20 and having an opening 36 around the connection of the elbow 19 with the pipe, so as to permit of the shifting of said tube. By virtue of this arrangement of the sleeves 31 it matters not which end of the container 3 is up, the end of the tube 20 which is at the lower end of the container is opened so as to permit the suction of fluid from the container into the cylinder 11 when the piston is being operated.

The container 3 is provided with a filler opening, preferably located in the cap 4, which is normally closed by means of a plug 37 screwed into a bushing 38 rigidly secured in said cap. In the drawings the filler opening is shown in the plane of the section, but in practice it is located at one side of the tube 21 so as not to be obstructed by the adjacent part of the fitting 10. A disk 39 is secured in the inner end of the plug 37 and is provided with apertures 40 which, in coöperation with the aperture 41, are adapted to admit air into the container 3. A valve 42 is normally urged by a spring 43 to close the aperture 41. The tension of the spring 43, however, is only sufficient to keep the opening 41 closed when the pressure in the container 3 is equal to that of the atmosphere.

The piston rod or tube 15 extends outwardly through the fitting 8 with which it has air-tight connection by means of a packing ring 44. A handle 45 is secured to the piston rod by means of which the piston is operated. A bolt 46 is threaded into the fitting 8 and provided with a ring 47 by means of which the device may be suspended from a nail or hook 48. An inclined cam shoulder or ledge 49 is formed on the handle 45 which is adapted to coact with a shoulder 50 on the bolt 46 for securing the piston 14 in its depressed position where it secures the valve 26 in position to shut

off communication with the nozzle 6. A notch 51 is formed in the ledge 49 in position to register with the shoulder 50 when the handle 45 is turned to the position shown in the drawings, and permits the locking or unlocking of the piston through rotation of the handle.

The operation of the device shown is as follows: Normally the device hangs on the wall suspended from a suitable nail or hook 48 and the handle 45 is turned so as to secure the valve 26 in its closed position as hereinbefore explained. When it is desired to use the device, it is removed from the hook 48 and the handle 45 is turned so as to bring the notch 51 into registration with the shoulder 50, which will allow the piston to be reciprocated in the cylinder 11. As the piston is drawn upwardly the fluid is drawn into the cylinder 11 through the inlet 12. The movement of the piston upwardly causes the fluid at the upper side thereof to be forced out through the tube 21 into the passage 17 and along the tube 18, and but through the aperture 7 in the nozzle 6. This upward movement of the piston 14 permits the spring 29 to retract the valve 26 so that the fluid may be discharged from the nozzle 6. The return movement of the piston causes the fluid to pass through the piston into the upper part of the cylinder 11. As the piston moves downwardly the tube 15 passing into the column of liquid, maintained in the cylinder by the valve 22, displaces the liquid and continues the discharge thereof out through the passages leading to the nozzle 6. When the pressure in the container falls below that of the outer atmosphere due to the fluid being forced out, air enters through the opening 41.

Although but one specific embodiment of this invention has been herein shown and described, it will be understood that numerous details of the construction shown may be altered or omitted without departing from the spirit of this invention as defined by the following claims.

I claim—

1. A device of the class described, comprising a container, a discharge nozzle in one end of said container and adapted to be used for directing the discharge of the contents from said container, a cylinder mounted within said container and having an inlet in the end thereof which is adjacent to the said one end of said container and having an outlet at the opposite end, a piston slidably mounted in said cylinder, a valve located in said inlet and adapted to permit fluid to flow from said container into said cylinder, a valve carried by said piston and adapted to permit the flow of fluid past said piston into the side of said cylinder which communicates with said outlet, and a tube located outside of said cylinder and

extending alongside thereof and connecting said cylinder outlet with said nozzle.

2. A device of the class described, comprising a container, a discharge nozzle in one end of said container, a cylinder mounted in said container and having an inlet in one end and an outlet in the opposite end, a fitting attached to the end of said cylinder and having passages formed therein, one of which communicates with said cylinder inlet and the other with said cylinder outlet and said nozzle, a tube supporting said fitting and providing communication between said other passage and said nozzle, a second tube located on the outside of said cylinder and connecting said outlet with said other passage, a piston slidably mounted in said cylinder, and valve mechanism adapted to control the admission of fluid from said container into said cylinder and the discharge thereof from said cylinder through said nozzle when said piston is reciprocated in said cylinder.

3. A device of the class described, comprising a container, a discharge nozzle located in one end of said container, a cylinder mounted within said container and having an inlet at one end and an outlet at the opposite end, a piston slidably mounted in said cylinder, a tube located outside of said cylinder and connecting said cylinder outlet with said nozzle, valve mechanism adapted to control the admission of fluid from said container into said cylinder and the discharge thereof from said cylinder through said nozzle, a valve arranged to shut off communication through said nozzle, a stem on said valve extending into said cylinder in position to be engaged by said piston when said piston is in its lowermost position, means normally urging said valve toward its open position, and other means adapted to hold said piston in its depressed position for closing said valve.

4. A device of the class described, comprising a container, a discharge nozzle in one end of said container, a cylinder mounted in said container and having an inlet in one end and an outlet in the opposite end, a fitting attached to the end of said cylinder and having passages formed therein, one of which communicates with said cylinder inlet and the other with said cylinder outlet and said nozzle, a tube supporting said fitting and providing communication between said other passage and said nozzle, a second tube located on the outside of said cylinder and connecting said outlet with said other passage, a piston slidably mounted in said cylinder, valve mechanism adapted to control the admission of fluid from said container into said cylinder and the discharge thereof from said cylinder through said nozzle when said piston is reciprocated in said cylinder, a valve arranged to shut

off communication through the tube connecting said other passage in said fitting and said nozzle, a stem on said valve slidably supported in said fitting and extending into said cylinder, and means normally urging said valve toward its open position, said valve being adapted to be held in its closed position when said piston is depressed.

5. A device of the class described, comprising a container, a discharge nozzle in one end of said container, pumping mechanism located in said container and having an outlet connected to said nozzle, a suction pipe connected to said pumping mechanism and terminating adjacent to the ends of said container, said pipe having ports in each of the ends thereof, and sleeves slidably mounted on the ends of said pipe and having ports therein adapted to be moved into and out of registration with the ports in said pipe, said sleeves being adapted to be normally urged by gravity to open the ports at one end of said pipe and close the ports at the opposite end so as to allow a suction of fluid from the lowest part of said container.

6. A device of the class described, comprising a container, a discharge nozzle in one end of said container, pumping mechanism located in said container and having an outlet connected to said nozzle, a suction pipe connected to said pumping mechanism and terminating adjacent to the ends of said container, said pipe having ports in each of the ends thereof, sleeves slidably mounted on the ends of said pipe and having ports therein adapted to be moved into and out of registration with the ports in said pipe, and means connecting said sleeves whereby they are adapted to be normally urged by gravity to simultaneously close the ports in one end of said pipe and open the ports in the other end so as to provide communication between said pumping mechanism and the lowest point of said container.

7. A device of the class described, comprising a container, a discharge nozzle in one end of said container, pumping mechanism located in said container and having an outlet connected to said nozzle, a suction pipe connected to said pumping mechanism and terminating adjacent to the ends of said container, said pipe having the ends thereof open, sleeves slidably mounted on the ends of said pipe, caps attached to said sleeves and adapted to form closures for the open ends of said pipe, said sleeves having ports therein inwardly of said caps, and means connecting said sleeves whereby they are adapted to be normally urged by gravity to simultaneously shift said caps to close one end of said pipe and open the other so as to allow a suction of fluid from the lowest part of said container.

8. A device of the class described, comprising a container, a discharge nozzle for said container, pumping mechanism located in said container and having the outlet connected to said nozzle, a valve for closing said nozzle slidably supported within said container and normally urged independently of the piston of said pumping mechanism to open said nozzle, and means carried by 10 said valve and adapted to be engaged by the piston of said pumping mechanism so as to hold said valve closed when said pumping mechanism is contracted.

Signed at Chicago this 21st day of Feb., 1914.
